ELECTRIC LAMP FOR MIXED LIGHT

Johann Buser, Riehen, near Basel, Switzerland, assignor to Buser-Lampen A.G., Riehen, near Basel, Switzerland, a Swiss company

Filed July 25, 1956, Ser. No. 599,953

3 Claims. (Cl. 315—46)

The present invention relates to a mixed light lamp for the simultaneous production of mercury-vapor arc light and incandescent light, which lamp consists of a super high pressure burner and a filament.

It has been shown that in lamps of the aforesaid type the temperature of the filament at the moment the lamp is switched on is quite substantially higher than in the normal operating condition. An economic light yield can thus only be obtained from the filament if the temperature in the stationary operating state reaches a level corresponding to the desired and admissible light efficiency. If this condition is fulfilled, the temperature of the circular-coil filament is quite substantially super-elevated in the heating up stage, which impairs the lamp's useful life. In order to give the lamp a reasonably long useful life, one would be compelled to have recourse, albeit not to the same extent, to the same means as are used in the construction of mixed light lamps with luminous elements connected in series; in other words, a compromise would have to be made which would mean nothing other than a loss of light efficiency in favour of longer lamp life. In view of these symptoms of disintegration and destruction which interact as a result of many different influences, the irregularity will become an in calculable problem.

According to the invention this difficulty of producing a mixed light by means of a mixed light lamp, such as for instance the one disclosed in U.S. Patent No. 2,669,676, is overcome by magnetically coupling the circuit of the filament, which receives approximately mains voltage, to the discharge circuit of the burner by means of a series connection to one winding section of the electric arc's stabilizing impedance, whereby a superelevation in the temperature of the filament when the lamp is switched on cannot result from the low gas pressure in the lamp's main vessel at this moment because of the initially low voltage at the electric arcs.

In mains with voltages of more than 220 volts a current limiting choke consisting of several winding sections is used to limit the current or stabilize the electric arc, and, according to the invention, the filament is connected in series to one winding section of this current limiting choke. In the case of single-phase alternating current operation current limiting chokes whose winding sections are preferably electrically interconnected in series are used for this purpose.

The endeavour is made for known reasons to operate the filament with as low a supply voltage as possible. In contradistinction hereto, mercury-vapor high and super high pressure lamps can be operated economically only at a supply voltage of 220 volts and over. For these reasons the production of a mixed light according to the invention is particularly suitable in alternating current mains in star circuit with neutral wire, the filament being joined on the one hand to the neutral wire and on the other to a mains phase via a winding section of the current limiting choke, which section is in series with said phase, while the discharge lamp together with its ap-

purtenant winding section of the current limiting choke is supplied from two different phases.

In mains with voltages of less than 220 volts, it is necessary for economic operations of the discharge lamp to transform the voltage to this economic operating value by means of a leakage-reactance transformer. When such leakage-reactance transformers are used, the circuits are magnetically coupled at the stabilizing impedance according to the invention in such a way that the stabilizing impedance, which consists of several winding sections, is loosely coupled magnetically via so-called stray yokes to the series field of the primary coil after the fashion of a leakage-reactance transformer.

A few typical embodiments of the invention are illustrated by way of example in the attached drawing, in which:

Figs. 1, 2 and 5 each show a mixed light lamp for general lighting purposes, such as have been disclosed for instance in U. S. Patent No. 2,669,676.

Figs. 3 and 4 each show a circuit layout according to the present invention.

Figs. 6 and 7 are two further mixed light lamps;

Figs. 8 and 9 are two examples of the inductance circuit.

The electric lamp for mixed light shown in Figure 1 includes a light-transmitting sealed envelope G_1 which is filled with an inert gas under pressure. Conducting means or terminals C_1 extend through the envelope G_1 and are connected with the filament W_1 for incandescent light. The second envelope G_2 is located within the envelope G_1 and is filled with mercury vapor under pressure which is higher than the pressure of the inert gas in the envelope G_1 . Other conducting means or terminals C_2 extend through the envelope G_2 and are connected with electrode means E , so that mercury vapor light is produced upon energization of the terminals C_2 . In accordance with the present invention, the device includes two inductive circuit means, which, in the embodiment shown in Figure 1, include winding sections A and B, respectively, of a current limiting choke. The section A is connected in series to the terminals C_1 and the section B is connected in series to the terminals C_2 . The sections A and B are inductively coupled to reduce the initial voltage appearing at the filament W_1 due to the high current flowing through the envelope G_2 filled with mercury vapor, immediately upon energization of the filament W_1 .

The arrangements of Figs. 1, 2 and 5 differ in detail in that in Figs. 1 and 5 the winding sections (A—B) of a current limiting choke are joined together in series after the fashion of an economy circuit and are connected to a single phase.

In Fig. 2 the winding sections (A—B) of a current limiting choke are electrically separated after the fashion of a pure transformation circuit so that the filament in series with one winding section (A) is connected on the one hand to a phase and on the other to the neutral wire, while the discharge lamp, which is in series with the winding section (B), is supplied from two mains phases.

Unlike Figs. 1, 2 and 5, Figs. 3 and 4 merely represent circuit layouts, the discharge lamp and the filament being only diagrammatically illustrated. In contradistinction to Figs. 1 and 5, the stabilizing impedance in these two circuit layouts is magnetically loosely coupled via so-called stray yokes to the series field of the dielectrically rigid primary coil after the fashion of a leakage-reactance transformer. This circuit becomes necessary if the maximum mains voltage available is less than 220 volts.

In the arrangement according to Fig. 3, the mains coil of the series field of the leakage-reactance transformer is directly connected to the mains, while the mains coil of the series field of the leakage-reactance transformer according to Fig. 4 is connected in series to that winding

section of the stabilizing impedance which is at the same time in series with the filament.

Fig. 5 of the drawing illustrates a typical embodiment of an electric lamp for mixed light, which is preferably intended for general lighting purposes and, as is diagrammatically shown, is connected to a stray choke. One end of the glow-lamp element is connected to a tapping point Z of the series unit. If, after the fashion of an auto-circuit, the end of the winding section A is joined to the start of the winding section B and the filament W₁ is joined to this connection—tapping point Z—the currents of both elements will flow through the winding section A, which is illustrated by the heavier lines. This auto or economy circuit can only be applied if a lamp provided with three-pole connector is operated on single-phase. The same end can also be achieved with the aid of a series unit having separate windings. The separation of the windings is necessary if the two elements have to be operated out-of-phase, for instance, if the filament has to be connected between phase and neutral wire, and the electric arc to two phases in the interests of better operation.

The effect is as follows: Immediately after the lamp is switched on and the electric arc ignited, the operating voltage of the electric arc drops, as is well known, to a few volts; the rest of the no-load voltage is at the choke; the specific voltage drop in volts per winding of the series unit is large during this period so that the partial voltage occurring between the choke input and the tapping point is also large. The potential value of this partial voltage has, if the windings are arranged in the same direction, a subtracting effect on the voltage of the filament. If the voltage rises owing to the pressure increase in the burner and the lamp's main vessel, the voltage drops via the choke, i.e. via the winding section to which the filament is connected. The partial voltage to be subtracted consequently decreases, or the operating voltage remaining in the filament increases. The synchronous increase of voltage and vapor pressure of the lamp is of great importance because this will ensure that the temperature of the filament is kept at least approximately constant. A further advantage worthy of mention is achieved by the circuit described, in that the electric arc is virtually no longer extinguished on passing through the zero point because the series unit acts as a leakage-reactance transformer and maintains an albeit strongly diminished flow of current by the tapping of an ohmic resistance in the period during which the burner's current changes its direction.

Fig. 8 illustrates diagrammatically a mixed light lamp with series unit, which lamp has two electric arcs and is operated with two phases. The mixed light lamps are shown merely symbolically and are marked ML.

Two standard burners can also be provided here in place of the two electric arcs accommodated in one bulb. The unit operates with two phases of power supply mains. When the lamp is first switched on, the voltage at the electric arcs is again very small, so that there is a correspondingly high voltage at the windings B. By poling the windings A accordingly, the magnetic flows produced can be made to counteract each other and thus cause the voltages to be subtracted. This, however, has the result that the voltage at the circular-coil filament is less than the mains voltage to begin with. As the pressure in the discharge vessel increases, and the voltage at the electric arcs rises and that at the windings B falls accordingly, the choking action exerted on the windings A also slackens so that after a while almost the full voltage appears at the circular-coil filament.

Fig. 9 shows a similar arrangement for single-phase operation. In the supply line here there is a transformer RT which may serve to keep the voltage automatically constant, but which may also be used to change the colour of the radiated light by altering the voltage.

A mixed light lamp produced for projection purposes, i.e. a lamp with a super high pressure burner and a

circular-coil grid stretched over one plane, has the great drawback that the directed light resulting intrinsically from the construction and designed for the illumination of a light field reveals extremely substantial deviations in

5 the composition of the light. In the centre of the luminous beam the light mixture consisting of mercury, vapor and electric arc is predominant so that a discolouration in the most important region of the picture is inevitable. This disadvantage is remedied or reduced to reasonable 10 proportions also by widening the concentrated electric arc into a light spot. This enlargement of the arc can be achieved, to a certain extent, by shaping the burner accordingly, i.e. by giving the burner a flat oval shape in the section transverse to the burner axis. It has been 15 shown, however, that it is virtually impossible to combat the local overloading of the vessel wall caused thereby with other means, in order that the absolutely essential high arc concentration can be maintained, while ensuring a reasonably long useful life. These difficulties are 20 overcome by providing two or more electric arcs in one and the same burner vessel. Since, in the case of super high pressure burners, the light arc starts by being slender at the lower electrode and then, because of the greater heat concentration, becomes bushy at the opposite, upper 25 electrode, the focal spot has the form of a droplet tapering towards the bottom. By utilizing this structure, a square or rectangular focal spot can be obtained by providing two electric arcs which burn, at the top, on an electrode common to both arcs and at the bottom on 30 separate electrodes. The V-shape of such an electric arc may also be balanced in respect of light intensity by correcting the circular-coil grid accordingly. This can be done in a simple manner by giving the circular coil the V-shape as well, but arranging it inversely to the burner.

35 Figs. 6 and 7 illustrate typical embodiments drawn partially in section. The burner G₂, of which a view is shown in Fig. 6, can only be designed for the maintenance of a discharge path having a flat oval cross-section and extending transversely to the burner's axis, 40 but may also represent the lateral elevation of the lamp according to Fig. 7. Similarly, three electrodes could also be sealed in at the bottom in order to produce three discharge paths. In this case, it would be advantageous to choose the central axis of symmetry for the third path. Obviously a star or even a delta layout could also be provided in the same way, thus also permitting a two-phase alternating current operation. For certain purposes even a three-phase system might offer quite considerable advantages. Fig. 8 illustrates a lamp 45 of this type designed for light projection. The electric arcs to be produced between the main electrode E₀ and the secondary electrodes E₁ and E₂ form a raised V, while the middle two arms of the circular-coil grid W₂ represent the inverse V-shape in normal position. The layout 50 of the circular-coil grid illustrated corresponds to a considerable extent to the toping-up factor necessary for the production of a focal spot dispensing light evenly in practically every direction, which is of very great importance.

60 As Figs. 5, 6 and 7 show, the lamp's main vessel G₁ is designed with an expansion chamber EK projecting into the surrounding air and designed to control the pressure of the gas-metal-vapor composition of said vessel in the event of said pressure rising too high. This 65 chamber (EK) serves as a pressure governor as the internal pressure of the high-percentage metal-vapor content of the gas-metal atmosphere is almost entirely dependent on the coldest point of the vessel. This obviates too great an increase in the mains voltage (excessive voltage) which, as is well known, increases more than proportionally to the rate of power input and consequently may lead to heat emissions which might cause a quite considerable increase in the vapor pressure. The pressure 70 of the lamp's main vessel, however, should be defined within wide limits by the surrounding atmosphere. The

shape and dimensions of said vessel will depend on local conditions or on the lamp's application. The use of this expansion vessel to centre and support the lamp construction is only of secondary importance. In lamps designed in this way the metal base body MB condenses in the expansion chamber. In addition, a residue which is not evaporated in stationary operation remains on the wall of the expansion chamber.

The expansion chamber EK is at the same time a safety valve as its wall is intentionally weakened.

Having now particularly described and ascertained the nature of my said invention and in what manner same is to be performed, I declare that what I claim is:

1. An electric lamp for mixed light, comprising a main sealed envelope having a light-transmissive wall, a pressure-exerting inert gas filling said envelope, conducting means extending through said wall of the envelope, a filament for incandescent light, said filament being located within said envelope and being connected to said conducting means, another envelope having a light-transmitting wall, pressure-exerting mercury vapor filling the second-mentioned envelope, the pressure of mercury vapor in the second-mentioned envelope being higher than the pressure of inert gas in the first-mentioned envelope, other conducting means extending through the wall of 25 the second-mentioned envelope, electrode means con-

nected with the second-mentioned conducting means for producing mercury vapor light upon energization of the second-mentioned conducting means, an inductive circuit means connected in series with the first-mentioned conducting means, another inductive circuit means connected in series with the second-mentioned conducting means, said two inductive circuit means being inductively coupled to reduce initial high voltage appearing at the filament upon energization of said filament due to the high current flowing through the mercury vapor-filled second-mentioned envelope.

2. A lamp in accordance with claim 1, wherein said two inductive circuit means are interconnected in series.

3. A lamp in accordance with claim 1, wherein the 15 second-mentioned conducting means consist of three terminals and said electrode means consist of three electrodes connected to the three terminals to provide two mercury vapor arcs which burn in the form of a V.
